UNITED STATES PATENT OFFICE

JASON A. FITCH, OF YOUNGSTOWN, OHIO, ASSIGNOR TO THE GENERAL FIREPROOFING COMPANY, OF YOUNGSTOWN, OHIO, A CORPORATION OF OHIO

EDGE CONSTRUCTION FOR FURNITURE TOPS

Application filed November 21, 1928. Serial No. 320,922.

This invention relates to tops for metal furniture, and more particularly to a novel edge construction for providing a finished edge and side for counter height sections, 5 metal desks, tables and the like.

A primary object of the invention is to provide a simple, practical and reliable means for concealing the edge of the linoleum surface usually used on metal tops, and to 10 also provide a finished appearance for the flange of the top below the bead portion which both protects and conceals the edge of the linoleum.

A further object of the invention is to provide a construction consisting of a minimum number of parts which may be readily assembled and held in their applied or fixed positions by the mere act of assembling the same in telescopic relation.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a sectional perspective view illustrating the invention.

Fig. 2 is a vertical cross sectional view illustrating the manner of assembling.

Fig. 3 is a detail perspective view of the 35 combined facing and locking strip.

Similar reference characters designate corresponding parts throughout the several figures of the drawings.

In the embodiment of the invention shown 40 in the drawings, the table top T is covered by a suitable surfacing of linoleum or the like designated generally as L, and the said top T is provided with down-turned flange T' which depends from the lower edge of the 45 linoleum surface. To provide a bead strip and also a facing to finish the edge of the top, the present invention contemplates the use of a novel bead strip A and a combined facing and locking strip B.

Referring first to the bead strip A it will

be observed that the same includes a rounded head portion 1 and a depending flange or body 2. The rounded head portion 1 is joined with the flange 2 by an angular or substantially horizontal connecting wall 3, and the latter is provided in the angle formed between itself and the outer surface of the flange 2 with a locking groove 4.

The combined locking and facing strip B is of substantially U-shaped or channel formation and is made of relatively heavy resilient metal. As shown in the drawings, this strip includes the inner and outer walls 5 and 6 respectively, the same being connected by the web 7 and the former having the out-turned guiding portion 5a while the latter is provided at its upper free edge with the inwardly offset locking rib 8 adapted to fit into the keeper groove 4.

As shown in Fig. 3 the strip B is made so that initially the walls 5 and 6 converge to provide a relatively constricted mouth or throat portion C between the inner edge of the rib 8 and the inner surface of the guiding portion 5a. Thus, when the strip is applied to the flange T' of the table top and the portion 2 of the bead strip, it is placed under tension to hold the parts tightly assembled.

By reference to Fig. 2 it will be observed that the bead strip A is placed beside the flange T' of the table top, and then the combined locking and facing strip B is moved upwardly, that is, into telescopic relation to said members until the locking rib 8 registers with the keeper groove 4. As previously indicated, the walls 5 and 6 of the combined locking and facing strip are made so that the entrance end of the channel member is narrower than the base, thereby keeping the entire locking strip under permanent tension when it is engaged with the flange of the table top and the body of the bead strip.

From the foregoing it will be apparent that the present invention includes a minimum number of parts namely, the bead strip A and the combined locking and facing strip B which may be moved into assembled relation by the mere act of fitting the facing strip over the flange of the top and the body portion of the bead strip. Also, the inner-

locked relation of the bead strip and the facing strip serves to securely hold the bead strip in position so that in the applied position, the bead strip and the facing strip are in effect a single unit so far as the down-turned flange of the desk or table top is concerned.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. In an edge construction for furniture tops, the combination with the top having a flange, of a bead strip having a keeper groove and a combined facing and locking strip including opposite resilient walls, one of said walls being provided with an outwardly turned guiding lip and the other being formed with an inturned locking bead adapted to fit into said groove when the parts are in assembled relation.
2. An edge construction for furniture tops comprising in combination with the top having a down-turned flange and a layer of surfacing material on the top, of a bead strip having a portion concealing the edge of the surface material for the top and also having a vertical body portion lying next to said flange, and a combined facing and locking strip movable in a direction parallel to the said down-turned flange to telescopically engage with said flange and the body of the bead strip.
3. An edge construction for furniture tops comprising in combination with the top having a down-turned flange and a layer of surfacing material on the top, of a bead strip having a portion concealing the edge of the surface material for the top and also having a vertical body portion lying next to said flange, a combined facing and locking strip movable in a direction parallel to said down-turned flange to telescopically engage with said flange and the body of the bead strip, and cooperating means on the combined facing and locking strip and on the body of the bead strip for interlocking said strips together.
4. An edge construction for furniture tops comprising in combination with a top member having a down-turned flange and a layer of surfacing material on the top, of a bead strip having a bead portion for concealing the edge of the surfacing material and also having a vertical depending body portion adapted to lie parallel with the flange, a substantially channel shaped combined facing and locking strip having the walls thereof normally bent toward each other and mov-

able in a direction parallel to the down-turned flange to telescopically fit over the body of the bead strip and the depending flange to hold the bead strip in position.

5. An edge construction for furniture tops comprising in combination with the top having a down-turned flange and a layer of surfacing material thereon, of a bead strip having a bead portion for concealing the edge of the surface material on the top and also having a depending body portion and a groove formed between the body portion and the bead portion, and a single resilient channel member movable in a direction parallel to the said down-turned flange to telescopically fit over the body of the bead strip and said flange, and an inturned rib carried by one edge of the channel member and adapted to fit in said groove of the bead strip.

6. In an edge construction for furniture tops, the combination with the down-turned flange of the top member and a bead strip overlying the face of said flange, of a single channel-shaped member having resilient side walls adapted to telescopically fit over and engage said flange and strip by movement in a direction parallel to said flange.

In testimony whereof I hereunto affix my signature.
